UNITED STATES PATENT OFFICE.

SAMUEL R. MUNSON, OF HARTFORD, CONNECTICUT, ASSIGNOR TO THE LANDERS, FRARY & CLARK, OF NEW BRITAIN, CONNECTICUT.

DESIGN FOR A CASE FOR PRICE-SCALES.

SPECIFICATION forming part of Design No. 33,735, dated December 18, 1900.

Application filed November 24, 1900. Serial No. 37,697. Term of patent 14 years.

To all whom it may concern:

Be it known that I, SAMUEL R. MUNSON, a citizen of the United States, residing at New Britain, in the county of Hartford and State of Connecticut, have invented and produced a new and original Design for a Case for Price-Scales, of which the following is a specification, reference being had to the accompanying drawings, forming part thereof.

10 Figure 1 is a front elevation of a case for price-scales, showing my new design. Fig. 2 is a rear elevation of a portion of the said case, taken from the right-hand end of Fig. 1. Fig. 3 is a side elevation or end view of the 15 same.

As shown in the drawings, the body of the case A is in the form of a long cylinder—that is to say, of a length about equal to twice its diameter. At each end there is a slightly- 20 projecting flattened bead or band 4, that merges into the sides or ends, with a rounded

corner 5. At the sides or ends there are a central rounded boss 6 and a sunken annular panel 7, as shown in Fig. 3. At the middle portion of the case on the top there is an upward projection 8, with straight side edges and a rounded upper end, as shown in Figs. 1 and 3, and at the bottom diametrically opposite the said projection 8 is an opening 9, as shown in Fig. 1. At the front of the case 30 there are three panels 10, 11, and 12, and on the rear, near one end, the panel 13, all of the design shown.

Having described my invention, what I claim as new, and desire to secure by Letters 35 Patent, is—

The design for a case for price-scales, as herein shown and described.

SAMUEL R. MUNSON.
